UNITED STATES PATENT OFFICE

2,460,463

PROCESS FOR THE NONCATALYTIC CRACKING OF A HYDROCARBON OIL

John W. Loy, Bartlesville, Okla., assignor to Phillips Petroleum Company, a corporation of Delaware

Application November 7, 1946, Serial No. 708,246

3 Claims. (Cl. 196—60)

1

This invention relates to the noncatalytic cracking of hydrocarbon oils. In one of its more specific aspects it relates to a reaction chamber of improved design in which to carry out mixed phase cracking of relatively heavy or high boiling petroleum fractions for the production of gasoline of improved quality and yield.

Processes for cracking of petroleum or hydrocarbon fractions have been divided into two types, catalytic and noncatalytic. The latter type is frequently called "thermal cracking," but this terminology should not be so limited in the strictest sense of the word since both methods involve super-atmospheric temperatures. However, the use of the term "thermal cracking" as applied to noncatalytic cracking is a very convenient and frequently used term, and will be used herein to mean noncatalytic cracking.

In the thermal cracking process the oil to be cracked may be heated in a tube or pipe heater and then at substantially reaction temperature discharged into a vessel generally termed a "reaction chamber." Reaction chambers frequently are merely cylindrical shaped steel vessels set on end, and of course are well insulated against loss of heat. The hot oil charge enters the chamber through the sidewall at a point near the top. Vapors leave through an overhead vapor line while bottoms leave through a bottom draw pipe.

One advantage of a reaction chamber as compared to coil cracking for heavy or residual oils is that the relatively nonvaporizable residuum may be removed from the bottom of the chamber after a short residence time at cracking conditions, whereas the remainder of the charge to the chamber, the vapor phase, receives a more prolonged treatment or reforming. An attempt to obtain the same result in conventional coil cracking usually results in the residuum portion being overcracked since it would be subjected to the same thermal treatment as the lighter portion and the process rapidly becomes inoperable through coking and plugging of the coil. The mere heating of wide cut fractions containing residuum materials frequently results in building up of a coke layer on the walls of the cracking tubes unless a very dense phase is maintained through high pressure. And further, high pressures sometimes unfavorably influence cracking products and their yields.

Reaction chamber cracking has many advantages for the cracking of heavy oils and these are well known in the cracking art.

In recent years there has been a general improvement in the octane number of gasoline

2

marketed to the consumer, nation wide, and where a refiner does not have catalytic cracking facilities, or where the oil to be cracked cannot readily be handled catalytically, existing reaction chamber equipment is found to be deficient in giving the quality of gasoline desired, concomitant with operable treatment of residuum product of the cracking process.

There is a limit to the flexibility and adequacy 10 of the conventional reaction chamber for cracking the vaporizable constituents without coking the residuum.

This obstacle can be overcome, I have discovered, by a rather simple and inexpensive improvement over existing equipment, which involves installation of an inverted vessel (lower end open) within a conventional reaction chamber.

One object of my invention is to provide an apparatus through the use of which thermal cracking of hydrocarbons is improved.

Another object of my invention is to provide a simple and inexpensive apparatus for use in conjunction with existing thermal cracking reaction chambers whereby the thermal cracking operation is improved with the resulting production of better quality gasoline.

Still another object of my invention is to provide means in thermal cracking reaction chambers by the use of which improved thermally cracked gasolines may be produced.

Still other objects and advantages will be apparent from a study of the following disclosure and attached drawing which respectively describes and illustrates the apparatus of my invention.

Figure 1 of the drawing illustrates one embodiment of my secondary chamber as installed within a thermal cracking reaction chamber.

Figure 2 is a horizontal section of the vessel taken on the line 2—2 of Figure 1.

Referring to the drawing, a vertically disposed cylindrical shaped reaction chamber 11 is fitted in its upper end with an overhead vapor line 12 which conducts vapors from the vessel to a subsequent process step. The bottom of the vessel is fitted with a bottoms draw-off line 13 through which bottoms or residuum passes to subsequent process steps or to cooling and storage. The vapor line 12 has a valve 4 for control of vapor flow while liquid flow through the bottoms line 13 is controlled by a valve 15.

A pipe 16 enters the chamber at about a midpoint, as shown in the drawing. A valve 17 in this pipe controls flow of materials therethrough.

This pipe 16 passes through the wall of the vessel 11 at an angle so that the inner end of the pipe may terminate in the cylindrical wall of an inner cylindrical vessel 18 as an "oval" shaped opening 19. Fluid from pipe 16 is intended to enter the inner vessel 18 tangentially to the inner wall thereof and substantially normal to the longitudinal axes of both vessels 11 and 18. The longitudinal axes of said vessels 11 and 18 substantially coincide.

In conventional thermal cracking reaction chambers the fluid inlet line corresponding to line 16 enters the vessel at a point somewhat near the top, and not necessarily at an angle to the vessel wall. The line usually enters the upper portion of the vessel at right angles to the vessel wall and terminates at the wall, that is, does not extend to a point within the volume of the vessel.

The inner vessel 18 is cylindrical in shape with closed top and an open bottom as illustrated in Figure 1. Vessel 18 is disposed a spaced distance from the ends of the outer chamber but is preferably closer to the bottom than the top of the outer chamber. There is no fixed relationship between the main chamber and the secondary chamber since the proportional size of the two will depend upon individual requirements. The cross sectional area of the inner chamber should, however, be less than the cross sectional area of the annular space between the two chambers, as is indicated in Figures 1 and 2. Tangential entry of the charge to the secondary chamber is preferred. The new design is adaptable to the commonly used two-coil operation wherein a relatively heavy fraction is preheated in one coil and a lighter fraction is preheated to a higher temperature in another coil, both streams passing to the same reaction chamber. The preheated lighter fraction would preferably enter the main chamber directly, however.

The purpose of this inner vessel with closed top and an open bottom is to make a more rapid and more nearly complete separation between vapors and residual oil or bottoms. Hot oil at cracking temperature flows from a heater, not shown, to my reaction chamber through the transfer line 16. A valve 17 is in line 16 at a point rather close to the point of inlet to the reaction chamber 11. Sufficient pressure is held upstream of this valve so that excessive cracking and/or vaporization will not occur.

Oil at cracking temperature passes through the transfer line 16 and through the pressure reducing valve 17 to enter the inner vessel, near its top, through the opening 19. The oil enters this vessel at a rather high velocity since on passage through the valve 17 considerable vaporization occurs, and further, the heated oil travels through the transfer line at a rather rapid rate. The oil then enters the vessel 18 at a point on its inner periphery and due to its velocity travels around the inner walls. The effect of gravity gradually causes the oil to pass downward and finally to drop from the walls of the inner vessel to the bottom of the outer vessel 11. In effect, the oil which is flowing around the walls of the inner vessel travels substantially in a helical path. Due to the relatively great centrifugal force acting on this rapidly traveling oil, the great difference in density between newly formed vapors and the residual oil, and the relatively small diameter of the internal vessel, separation between the oil and vapor is much more rapid than when the oil to be cracked enters a reaction chamber in the conventional manner. In other words,

the ratio of the respective residence times at cracking temperature of the liquid and vapor phases is much reduced.

Vapors formed by vaporization and by cracking of liquid and vaporous hydrocarbon pass downward within this inner chamber, then change direction to flow upward in the annular space between the chamber 18 and the walls of the main reaction chamber 11. By so doing, all or substantially all liquid or mist is removed from the vapors and the vaporous material leaving the reaction chamber by the overhead line 12 is free from residual or tarry material. This operation may be contrasted with conventional operation in which the transfer line discharges its mixed vaporous, liquid and tarry material into the top of the chamber and the liquid and tarry mist is carried out either on overhead or bottom line to a dephlegmation and subsequent fractionation steps. In other words there is less or substantially no liquid or tar entrainment in the overhead vapors leaving my reaction chamber 11. The secondary chamber should not be so close to the bottom of the primary chamber that drops of liquid or mist cannot be separated therefrom.

Due to the rapid rate of travel of liquid around the walls of the inner vessel 18, there may be little deposition of coke. The tar rapidly falls or drains to the bottom of the chamber 11 and is withdrawn through pipe 13 as controlled by valve 15. Little or no liquid level is maintained in the vessel 11, or even some little vapor may be withdrawn through the tar draw 13 to assist in the more rapid withdrawal of the bottoms. Speedy withdrawal of these high temperature bottoms shortens, of course, their residence time in the chamber at reaction temperature and accordingly assists in minimizing coke formation therein.

Withdrawal of too much vapor with the bottoms tends to prevent normal vapor flow through the overhead vapor line, the vapor within the chamber tends to become overcracked, and more extensive dephlegmating equipment is required external to the reaction chamber.

With the equipment revision described, the temperature of the charge to the chamber can be elevated considerably over what would be possible with the old design (or the depth of cracking otherwise increased) and this will effect an important increase in the degree of cracking of the vapor phase with a corresponding increase in the quality of gasoline yielded from the process, without coking the residuum product or otherwise impairing its characteristics as regards its disposition in commercial fuel oil markets.

By the use of the inner vessel 18 as herein disclosed the residence time of the vapor phase within the chamber is about the same as if the inner vessel were not used, but the residence time of the residual liquid and tarry material is shortened, so that due to the formation of less coke within the chamber longer "onstream" periods can be realized.

The support members for the inner vessel 18 may be of any type or kind desired and found suitable for the purpose at hand. It is usually better to support this inner vessel from its top than from the bottom, since no support members are then present to interfere with eventual removal of any coke from the chamber bottom. For purposes of illustration some support members 20 are shown as attaching the inner vessel to the reaction chamber.

Materials of construction for the main reaction chamber may be selected from among those ordinarily used while the inner vessel 18 may preferably be made from relatively light and inexpensive steel plate and rigidly supported. The outer chamber is of course well insulated against loss of heat.

It will be obvious that the relative size of the secondary chamber 18 may be varied, and its position altered with respect to the bottom of the primary chamber 11, as individual or specific conditions warrant.

Having disclosed my invention, I claim:

1. An improved method for noncatalytically cracking hydrocarbon oil which comprises in combination the steps of heating said oil to its cracking temperature; reducing the pressure on said oil, introducing said oil tangentially and at a relatively high velocity into a cylindrical separation zone which is closed at its top; rapidly separating vapors and residual liquid in said separation zone by centrifugal force; passing said separated products downwardly from said separation zone into an enlarged reaction zone surrounding and extending beyond each end of said separation zone; removing residual liquid from the bottom of said reaction zone; passing said vapors upwardly, at a relatively low velocity, around said separation zone and into the upper portion of said enlarged reaction zone; maintaining said vapors in said reaction zone for more complete cracking; and removing effluent vapors from the upper portion of said reaction zone.

2. An improved method of noncatalytically cracking hydrocarbon oil which comprises in combination the steps of heating said oil to its cracking temperature; reducing the pressure on said oil; introducing said oil, at a relatively high velocity, tangentially into a cylindrical separation zone at a point adjacent its top, which zone is unobstructed except for being closed at its top; rapidly separating vapors and residual liquid in said separation zone by centrifugal force; passing said separated products downwardly from said separation zone into an enlarged reaction zone 45

surrounding and extending beyond each end of said separation zone; removing residual liquid and a small portion of vapors from the bottom of said reaction zone; passing the remaining portion of vapors upwardly, at a relatively low velocity, around said separation zone and into the upper portion of said enlarged reaction zone; maintaining said vapors in said reaction zone for more complete cracking; and removing effluent vapors from the upper portion of said reaction zone.

3. An improved method for noncatalytically cracking hydrocarbon oil which comprises in combination the steps of heating said oil to its cracking temperature; reducing the pressure on said oil; introducing said oil tangentially and at a relatively high velocity into a cylindrical separation zone which is closed at its top; rapidly separating vapors and residual liquid in said separation zone by centrifugal force; passing said separated products downwardly from said separation zone into an enlarged reaction zone surrounding and extending beyond each end of said separation zone; removing residual liquid from the bottom of said reaction zone; passing said vapors upwardly, at a relatively low velocity, around said separation zone and into the upper portion of said enlarged reaction zone; and removing effluent vapors from the upper portion of said reaction zone.
